LAMP STRUCTURE

Norbert P. Worden and Charles F. Foley, Detroit,
Mich., assignors to C. M. Hall Lamp Company,
Detroit, Mich., a corporation of Michigan

Original application March 29, 1937, Serial No.
133,666. Divided and this application January
3, 1938, Serial No. 183,177

6 Claims. (Cl. 240—41.5)

This invention relates generally to lamps for motor vehicles and constitutes a division of our application filed March 29, 1937, bearing Serial No. 133,666.

One of the essential objects of the invention is to provide a lamp of the type mentioned wherein approximately one-half of the housing is a die casting that is adapted to be mounted upon a suitable support such as a fender or radiator of a motor vehicle and is provided with means for carrying the other elements of the housing including a sheet metal cover and a bezel.

Another object is to provide a lamp wherein a hermetically-sealed light unit is provided with an adjustable mounting carried by the die casting and bezel.

Another object is to provide a lamp wherein the bezel has a lower section integral with the die casting and has a separate upper section that is detachably fastened to the lower section to facilitate removal and replacement of the fluted and prisms lens.

Another object is to provide a lamp that is comparatively inexpensive to manufacture and install, and wherein the mounting means for the hermetically-sealed unit is simple in construction, readily accessible and easily adjusted as desired.

Other objects, advantages and novel details of construction of this invention will be made more apparent as this description proceeds, especially when considered in connection with the accompanying drawing, wherein:

Figure 1 is a bottom plan view of a lamp embodying our invention;

Figure 2 is a front elevation of the structure illustrated in Figure 1;

Figure 3 is a sectional view taken approximately on the line 3—3 of Figure 2;

Figure 4 is a sectional view taken substantially on the line 4—4 of Figure 3;

Figure 5 is a sectional view taken substantially on the line 5—5 of Figure 2.

Referring now to the drawing, A is a lamp housing having a die cast base section 1, a sheet metal cover 2, and a bezel 3. As shown, the base section 1 forms approximately the lower half of the housing and is provided at its forward end with a supporting portion 4 for the bezel. Preferably the cover section 2 is formed of sheet metal of inverted trough configuration and has its lower edges seated within a suitable groove or channel 2a in the upper edges of the base section 1.

Any suitable means such as the bracket 5 and screw 6 may be employed for fastening the

cover 2 to the die casting 1. As shown, the bracket 5 is fixed to the bottom 7 of the casting 1, while the screw 6 extends through a suitable opening 8 in the cover 2 and threadedly engages said bracket. Likewise, any suitable means (not shown) may be engaged with the bottom 7 of the casting 1 for mounting purposes.

The lighting element is preferably in the form of a hermetically-sealed unit 9 containing a filament 10 and having a lens 11 and reflector 12 at 10 the front and rear thereof. However, if desired, an open reflector and one or more bulbs carried thereby (not shown) may be used instead. In either case the lighting element would be provided with an adjustable mounting 13. As shown, this adjustable mounting is carried by lugs 14 and 15 integral with the base section 1 and by the bezel 3. As shown, the bead 16 of the hermetically-sealed unit is seated in a semi-circular flange 17 of U-cross section projecting laterally from the supporting ring 18 and is held at the top to said ring by a suitable clip 19. The ring 18 is substantially parallel to the lugs 14 and 15 and is supported therefrom by screws 20 that extend through the ring 18 and lugs and threadedly engage adjusting nuts 21 on the back of the lugs. Coil springs 22 are sleeved upon the screws 20 between the ring 18 and the lugs 14 and 15, respectively, to hold the ring in proper position relative to the lugs according to the adjustment of the screws 20. A screw 23 tapped in the bezel 3 extends through the ring 18 and engages an adjusting nut 24 on the back of the ring, while a coiled spring 25 is sleeved upon the screw 23 between the ring 18 and bezel 3.

In the present instance the supporting portion 4 of the bezel is integral with the base section 1, but has a separate upper section 26 that is fastened by screws 27 to the lower section 4. The fluted prisms lens 27 fits within the bezel and 40 has an annular flange 28 that fits within an annular groove 29 in said bezel. 30 is a channel gasket in the groove 29 receiving the edges of the flange 28.

If desired, a bead 31 may be provided integral with the base section 1 at the upper edges thereof for overlapping the lower edges of the cover section 2 and may be covered by a chromium plated sheet metal bead (not shown).

Thus, with this construction the light projected from the unit 9 may be directed or aimed as desired by adjustment of the nuts 21 and 24. Such nuts are within the housing and therefore normally concealed. However, they may be read-

ily reached for any purpose by simply opening or removing the sheet metal cover 2.

What we claim as our invention is:

1. In a lamp structure, an ovoid casing split longitudinally substantially along a horizontal plane axially of the lamp and provided at one end with a bezel, the lower section of said casing being attachable to a support, the upper section of said casing being mounted on said lower section and bezel, a light unit in said casing, and a mounting for said unit including a lug on the lower section of said casing, a supporting ring in the casing adjacent said lug and bezel, a seat for said unit carried by said ring, and means 10 adjustably connecting said ring to said lug and bezel.

2. In a lamp structure, an ovoid casing split longitudinally substantially along a horizontal plane axially of the lamp and provided at one end with a sectional bezel, one section of said bezel being integral with one section of said casing, the second section of said bezel being separate from the casing and detachably connected to the first mentioned section of the bezel, a light 20 unit in said casing, and a mounting for said unit including a lug on one section of said casing, a supporting ring in said casing adjacent said lug and bezel, a seat for said unit carried by said ring, and means adjustably connecting said ring to said lug and to one section of said bezel.

3. In a lamp structure, an ovoid casing split longitudinally substantially along a horizontal plane axially of the lamp and provided at one end with a bezel, the lower section of said casing being attachable to a support, the upper section of said casing being mounted on said lower section and bezel, a light unit in said casing, and a mounting for said unit including a lug on the lower section of said casing, and a holder for 35 said unit suspended from said bezel and adjustably connected to said lug.

4. In a lamp structure, an ovoid casing split

longitudinally substantially along a horizontal plane axially of the lamp and provided at one end with a sectional bezel, one section of said bezel being integral with one section of said casing, the second section of said bezel being separate from the casing and detachably connected to the first mentioned section of the bezel, a light unit in said casing, and a mounting for said unit including a lug on one section of said casing, and a holder for said unit suspended from the second section of said bezel and adjustably connected to said lug. 5

5. In a lamp structure, a casing provided at one end with a sectional bezel, one section of said bezel being integral with said casing, the second section of said bezel being separate from the casing and detachably connected to the first mentioned section of the bezel, a light unit in said casing, and a mounting for said unit including a lug within and rigid with a part of said casing, a supporting ring extending transversely of 10 said casing and adjustably connected to said lug and second section of the bezel, and a seat for said unit carried by said ring. 15

6. In a lamp structure, a casing provided at one end with a bezel, a light unit in said casing, and a mounting for said unit including a lug projecting from the inside of said casing, a supporting holder for said unit having attaching portions at spaced points thereof, a screw projecting from 20 the bezel through one of said attaching portions, an adjusting nut on said screw for urging the holder toward the bezel, spring means on the screw between the holder and bezel, a screw projecting from another of said attaching portions and adjustably engaging said lug, an adjusting nut on the second mentioned screw engageable with the lug to urge the holder away from said bezel, and spring means on the second mentioned screw between the holder and lug. 25
